UNITED STATES PATENT OFFICE.

JOHN A. GUSTUS, OF DETROIT, MICHIGAN, ASSIGNOR TO DETROIT BUTCHER SUPPLY COMPANY, OF DETROIT, MICHIGAN, A CORPORATION OF MICHIGAN.

COUNTER INCLOSURE.

Application filed August 28, 1922. Serial No. 584,683.

To all whom it may concern:

Be it known that I, JOHN A. GUSTUS, a citizen of the United States of America, residing at Detroit, in the county of Wayne and State of Michigan, have invented certain new and useful Improvements in Counter Inclosures, of which the following is a specification, reference being had thereto in the accompanying drawings.

10 The invention relates to counter inclosures and refers particularly to that type combining a display compartment and a refrigerating compartment in communication therewith. One of the objects of the invention is to provide a simple construction of frame for supporting a door which is movable upwardly and outwardly from closed position to open position. Another object is the provision of a frame member having 20 a cross bar upon the upper end of which a top is supported and upon the lower end of which the door is adapted to be supported, sufficient clearance being provided below the top for the door. Further objects of the invention reside in the support for the pipes 25 through which the refrigerant flows; and in the novel features of construction and combinations and arrangements of parts as more fully hereinafter set forth.

30 In the drawings:

Figures 1 and 2 are perspective views of a counter inclosure embodying my invention;

Figure 3 is a transverse section therethrough;

35 Figure 4 is a front elevation of a portion thereof;

Figures 5, 6 and 7 are respectively cross sections on the lines 5—5, 6—6, and 7—7 of Figure 3.

40 1 is the display compartment of the counter inclosure, and 2 the refrigerating compartment at the rear thereof and communicating therewith. The frame of the display compartment comprises the spaced

45 parallel frame members 3 each preferably of one-piece construction, comprising the upright bar 4, the top bar 5, and the downwardly and rearwardly inclined bar 6, which latter has a foot flange 7 resting upon

50 and secured to the top 8 of the refrigerating compartment. Both the upright and downwardly and rearwardly inclined bars are of T cross section as shown respectively in Figures 5 and 7, while the top bar is of I cross section as shown in Figure 6. 9 are

end closures of the counter inclosure secured to the end frame members, 10 are the front closures, and 11 the top closures, all preferably formed of glass and secured to the frame members. The top bars of the frame members are of progressively increasing depth from front to rear, and the top closures are supported upon the lateral flanges at the upper edges of these top bars.

12 are sliding doors at the rear of the display compartment and adapted in closed position to rest upon the ledges 13 formed by the opposed lateral flanges 14 at the lower edges of the downwardly and rearwardly inclined bars. These closures abut the front edges of the top of the refrigerating compartment and preferably have a sealing strip 15 at their upper edges which are adapted to engage the under surface of the tops of the display compartments near their rearward edges to completely close the space between the top of the counter inclosure and the top of the refrigerating compartment. The doors may be readily slid upwardly and forwardly from their closed position to rest upon the lateral flanges 16 at the lower edges of the top bars 5, sufficient clearance being provided below the top 11 for the movement of the doors.

The refrigerating compartment 2 has extending longitudinally thereof the pair of pipes 17 and 17' adapted for the passage of the refrigerant. To support these pipes, I have provided the frame members 18 which rest upon the bottom of the refrigerating compartment and are secured to the rear and top walls thereof. These frame members have vertical webs 19 adapted to engage the rear walls of the pipes and also have the lower webs 20 which are recessed at 21 to engage the lower pipe 17'. 22 is a clamp for each frame member having a nose 23 insertable upon the upper and lower pipes and resting upon the lower pipe to force the same into engagement with its recess. Each clamp is L-shaped and the inside of its curve engages the outer wall of the upper pipe to force the same into engagement with the vertical web of the frame member. The upper and free end of the clamp is laterally movable into engagement with the depending lug 24 formed at the forward edge of the upper portion of the frame member, an upper web 25 preferably extending from the vertical web to the lug to reinforce the same.

2

In order to facilitate the cleaning of the refrigerating compartment, provision is made for the insertion of trays 26 between the frame members 18 and resting upon the bottom of the compartment. These trays have apertures 27 in their bottom which register with a gutter 28 extending longitudinally in the upper face of the bottom of the compartment, this gutter in turn communicating with a suitable drain 29 to drain any condensation collecting upon the frame members 18 into the trays. The lower portions of the frame members have outwardly and downwardly curved flanges 30 which are spaced sufficiently above the compartment to permit of the ready insertion or removal of the trays therebeneath, the ends of these trays extending below these flanges. With this arrangement, it will be seen that any condensation upon the pipes or frame members will be collected by the trays and then drained through the apertures in the bottom of these trays into the gutter in the bottom of the compartment and then into the drain from the gutter. Also, these trays may be readily removed to be cleaned and then replaced.

From the above description, it will be seen that I have provided a construction in which the door rocks in being moved to open or closed positions and in which the door automatically moves to closed position after it has been moved outwardly a sufficient distance to bring its center of gravity beyond the fulcrum points at the upper ends of the ledges 13. Also, these doors may be readily removed from the frame to permit cleaning. Still another important consideration is the arrangement of clamps for securing the refrigerating pipes in place, these clamps being simple in construction and being readily applied or removed. Another very important feature resides in the arrangement of refrigerating compartment frame members with the trays below their outwardly and downwardly curved flanges upon their lower portions, whereby the refrigerating compartment may be more easily cleaned.

What I claim as my invention is:

50 1. In a counter inclosure, a pair of spaced top bars having flanges along their lower edges, downwardly and rearwardly inclined bars having opposed lateral flanges along their lower edges connecting with the lower flanges respectively of said spaced top bars, a top supported on said top bars, and a door normally resting freely upon the said lateral flanges of the inclined bars and adapted to be lifted at its rear end to slidably engage the lower flanges of the said top bars along the length of the opposite edges of the door when slid into open position.

55 2. In a counter inclosure, a pair of spaced top bars having flanges along their lower edges, downwardly and rearwardly inclined

bars having opposed lateral flanges along their lower edges connecting with the lower flanges respectively of said spaced top bars, a top supported on said top bars, said first mentioned flanges sloping rearwardly away 70 from said top, and a door normally resting freely upon the said lateral flanges of the inclined bars and adapted to be lifted at its rear end to slidably engage the lower flanges of the said top bars along the length of the 75 opposite edges of the door when slid into open position.

3. In a counter inclosure, a pair of spaced top bars having flanges along their lower edges, downwardly and rearwardly inclined 80 bars having opposed lateral flanges along their lower edges connecting with the lower flanges respectively of said spaced top bars, a top supported on said top bars, a door normally resting freely upon the said lateral flanges of the inclined bars and adapted to be lifted at its rear end to slidably engage the lower flanges of the said top bars along the length of the opposite edges of the door when slid into open position, and a sealing 85 strip along the forward edge of the door normally engaging the top.

4. In a counter inclosure, a pair of spaced top bars having supporting flanges along their lower edges sloping rearwardly and 90 downwardly, a top supported by said top bars, spaced inclined bars having opposed lateral supporting flanges along their lower edges connecting with the lower flanges respectively of said spaced top bars, a door 100 normally supported along its opposite edges upon the flanges of the inclined bars and having its upper forward edge normally overhanging the connected portions of the supporting flanges of the top and inclined 105 bars respectively and engaging said top, said door being slidable beneath the top.

5. The combination with a plurality of frame members having horizontal members for supporting a pipe, of a plurality of trays 110 each insertable below and between said horizontal members, and outwardly extending flanges on said horizontal members to guide the drip to the trays.

6. In a counter inclosure, the combination 115 with spaced frame members each having a substantially horizontal portion of I cross section and progressively increasing in depth from front to rear thereof and each having a downwardly extending portion of 120 inverted T cross section connecting into the rear end of said substantially horizontal portion, of a closure resting upon said downwardly extending portion when in one position and slidable to rest upon said substantially horizontal portions when in another 125 position.

In testimony whereof I affix my signature.

JOHN A. GUSTUS.
